CLAIM

The ornamental design for a mesh hat as shown and described.

DESCRIPTION

FIG. 1 is a front, right and top perspective view of a mesh hat, showing our design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof; and,

FIG. 7 is a top plan view thereof.

The broken lines depict environmental structure and form no part of the claimed design.
